E. TAYLOR.
AUTOMATIC SUBSTATION.
APPLICATION FILED JULY 7, 1915.

1,237,973.

Patented Aug. 21, 1917.

UNITED STATES PATENT OFFICE.

EDWARD TAYLOR, OF CHICAGO, ILLINOIS, ASSIGNOR TO GENERAL ELECTRIC COMPANY,
A CORPORATION OF NEW YORK.

AUTOMATIC SUBSTATION.

1,237,973.

Specification of Letters Patent. Patented Aug. 21, 1917.

Application filed July 7, 1915. Serial No. 38,620.

To all whom it may concern:

Be it known that I, EDWARD TAYLOR, a citizen of the United States, residing at Chicago, in the county of Cook, State of Illinois, have invented certain new and useful Improvements in Automatic Substations, of which the following is a specification.

This invention relates to automatic substations of the type employing a rotary transformer which is adapted to interconnect a supply circuit and a distribution circuit.

Automatic substations of this type are particularly applicable to electric railway systems where the schedule of operation is such that the substation is only needed during a small portion of the whole time. Since no attendant is required, all expense in this connection is avoided, and, in addition, the light load losses attendant upon the operation of the ordinary substation are entirely eliminated. One object of my invention, then, is to produce an improved construction of automatic substation of this type.

In connection with such a substation, I have found it to be particularly important that the sequence of operation of the various switches controlling the rotary transformer shall be exactly determined, and also that the intervals between the operation of the various switches should be properly controlled. It is another object of my invention to provide apparatus for an automatic substation whereby the sequence of operations and the intervals therebetween shall be mechanically and positively determined.

It has been found that the ordinary circuit-breaker interposed between the rotary transformer and the distribution circuit is not in all cases a satisfactory means of protection for the substation from overloads on the distribution circuit. The disrupting of heavy currents frequently causes sudden induced voltages in the distribution circuit which may exceed 200% of the normal voltage. Where the distribution circuit is a railway trolley, such voltages may cause flashing-over of the commutators and motors, or may puncture the motor insulation. On the other hand, the simultaneous starting of several cars within the zone of operation of the substation may produce such

an overload that the ordinary circuit-breaker would be blown out. In the usual arrangement, the cars would then be fed with current from a distant station, but at a greatly reduced voltage; their acceleration would, therefore, be greatly decreased, and, as a consequence, the counter-electromotive force produced would also be decreased. Suppose, then, that the operator at the substation closes the circuit-breaker, and throws the normal voltage on the trolley line. The motor equipment is not in a condition to receive such a voltage, and, as a consequence, severe trouble may result. It is accordingly, another object of my invention to provide means of overload protection which shall overcome these difficulties and effectively protect the substation and the distribution circuit.

My invention will be more readily understood from the following description, taken in connection with the accompanying drawing, in which the single figure is a diagrammatic view illustrating the apparatus employed and the connections used for my automatic substation.

The supply circuit A. C. is adapted to be connected to the alternating current terminals of the rotary transformer R. T., which as shown is a rotary converter, by means of the oil switch O. S., through the transformer T and either one or the other of the switches R and S. The rotary converter is of the usual construction, and is provided with the shunt field windings *a*, *b* and *c*, and with the series field winding *d*. This series field winding is arranged so that it may be shunted by means of a resistance *e*. The direct current terminals of the rotary converter are arranged to be connected to the distribution circuit D. C., through a series of resistances 50 and the coils of certain relays, to be later described.

This apparatus is arranged to be controlled by means of electromagnetic switches, most of which are energized in sequence by means of a controller C. The function of the controller is to mechanically determine, by means of the relative positions of the contacts carried thereby, the exact sequence of operation of the switches which it controls. In its preferred form, I have illustrated this controller as being made up of fixed contact fingers leading to

the coils of the various electromagnetic switches, and of a cylindrical drum carrying metallic contacts, by means of which the various fingers may be interconnected 5 in the desired manner and in the desired sequence. This form of controller is well known in the art, and no further description thereof is deemed herein necessary.

For the purpose of rotating the cylindrical drum of the controller C, I have illustrated a motor M, which is mechanically connected thereto. Automatic means are then provided for controlling this motor, so that preferably the station will be operated 15 in accordance with the load conditions of the distribution circuit D. C.

When the station is applied for use in connection with an electric railway, I find it convenient to make this automatic apparatus of such a form that the station will be started when the voltage of the distribution circuit decreases below a predetermined value, and will be stopped when the power transferred by the rotary transformer is 25 less than a predetermined amount.

It is believed that the coöperation and function of the various elements will be more readily understood when considered in connection with their mode of operation, 30 and to this end I will describe the operation of my substation when the load conditions of the distribution circuit are such as to require its use.

Let us assume that the distribution circuit 35 is energized, but that its voltage is considerably below normal, say, for example, 400 volts. A relay 1 will be energized, and immediately closes its upper contacts. The lower contacts of this relay are connected to 40 the magnetic core by means of a spring, and their closing is delayed by means of a suitable retarding device such as a dashpot, which may be suitably designed so that the lower contacts will close after any desired 45 interval. The particular construction of this relay is required only when several automatic substations of this type are arranged on a single distribution circuit. In that case, it is desirable that the stations shall 50 not all be started at the same time, as might happen at the beginning of a day, when the distribution circuit is first energized, but that their starting should be retarded for definite intervals. The contact-making volt- 55 meter 2, which is responsive to the voltage of the distribution circuit, will fall to a position so that its movable arm makes contact with the upper fixed contact point, and thereby energize the relay 3. This relay is 60 thereupon raised, and completes a holding circuit through its upper contacts. At the same time it energizes the potential coil g of the master relay 4, and raises the same to 65 close a circuit through the sliding contacts and the contacts of the relays 23 and 24 for

energizing the relay 5. This relay will then be lifted and thereby close a circuit through the controller to energize the relay 6. The energization of this relay will supply direct current to the motor M and to the brake coil B in series therewith. The brake coil B is used in connection with an electromagnetic brake, so designed that when the coil is energized, a friction brake will be released, and when the coil is deenergized, a friction brake will be applied. As soon as the controller C moves from its neutral position α to its first position m , the relays 8 and 9 will be energized. The closing of the relay 9 will energize the closing coil 80 of the oil switch O. S., and close the same. The energization of the relay 8 will then energize the relay 7 through the contacts of the controller, and this, in turn, will then energize the coil 10 of the starting switch 85 S, and thereby supply alternating current energy at a reduced potential to the terminals of the rotary transformer R. T. This will start the rotary transformer in motion. Further movement of the controller to the position α will simply insert a resistance 26 in series, through the interlock contacts of the oil switch O. S., with the relays 8 and 9. The resistance 26 will be so proportioned that sufficient current will flow 90 in this circuit to hold these relays closed, but will be of such value that the current supplied will not be sufficient to initially close the relays. In the event, therefore, of a momentary interruption of power on the 100 distribution circuit during the subsequent cycle of operations of the controller C, the relays 8 and 9 will open, and cannot be closed until the controller returns to its original neutral position α . Obviously, the 105 opening of the relay 9 will deenergize the closing coil of the oil switch O. S., allowing the same to open, and thereby prevent further acceleration of the rotary transformer R. T. Upon the return of normal 110 voltage on the distribution circuit, the master relay 4 will drop to its lower position and thereby energize the relay 23 and cause the controller to be returned to the neutral position α . The drum of the controller now 115 moves ahead for several seconds, without altering the existing conditions. This interval gives sufficient time to allow the acceleration of the rotary transformer. When the controller position p is reached, however, the field break-up switch 11 will be energized, thereby connecting the shunt field windings a , b , and c , in series with one another, and the resistance E. R. across the distribution circuit D. C. This provision of 120 a switch for breaking up the shunt field windings of a rotary transformer into several portions is well known in the art, and is for the purpose of reducing the voltage 125 which might be induced therein during the 130

starting period. When the controller position q is reached, the switch 12 will be energized, and short circuit the resistance E. R., thereby applying the full voltage of the distribution circuit to the shunt field of the rotary transformer. Between the controller positions q and r , the relay 7, and, consequently, the magnet 10 are deenergized, thus causing the opening of the starting switch S. At the position r , the magnet 13 of the running switch R will be energized, and the switch closed.

It will be noted that the switches R and S are electrically interlocked, and that each one is provided with a resistance which is inserted in series with its coil as soon as the corresponding switch is closed. The provision of these resistances cuts down the current supplied to the coils 10 and 13, and decreases the sparking at the contacts of the controller C when their circuits are opened. When the running switch R is closed, the full voltage of the supply circuit A. C. will be applied to the rotary transformer. At the next position s of the controller C, the switch 14 will be energized, thereby shunting the series field d of the rotary transformer by means of the resistance e . At the position t , the switch 15 will be energized through interlocks on the switches 11, 12, and 13, and will thereby connect the direct current terminals of the rotary transformer to the distribution circuit through the resistances 50, the holding coil h of the master relay 4, and the current coil of a reverse current relay 22. At the steps u , v and w the switches 16, 17 and 18 will be energized in turn to successively short-circuit portions of the resistance 50. The energizing circuits of these relays are controlled by means of relays 19, 20, and 21, which are responsive to the power transferred by means of the rotary transformer, and, in this case, are energized from a current transformer on the alternating current side thereof. The relays 19, 20, and 21 are so designed that they are responsive to different values of current, and will, consequently, open in succession as the power transferred exceeds certain predetermined values, corresponding to the settings of these relays. The function of these relays will be later considered more at length. When the position w is reached, the energizing circuit of the relay 6 is broken, thereby stopping the controller at this, its running position. Power will now be supplied to the distribution circuit D. C., and the voltage of said circuit will be determined by the voltage of the direct current terminals of the rotary transformer. As soon as this voltage reaches the normal voltage of the distribution circuit, say 550 volts, the movable arm of the contact-making voltmeter 2 will touch its lower fixed contact and short-

circuit the relay 3, thereby dropping out the same and deenergizing the potential coil g of the master relay 4. The master relay will, however, be retained in its upper position by means of the holding coil h so long as the current therein exceeds a predetermined value. The reverse current relay 22 is so designed that when the power transferred exceeds the predetermined value by which the holding coil h is designed to hold up the master relay 4, its moving contact will be moved to the left, thereby inserting a resistance 22 in series with the coil of the contact-making voltmeter 2. This will so reduce the voltage on the contact-making voltmeter that its movable arm will immediately touch the upper fixed contact and thereby reenergize the relay 3 and the potential coil of the master relay 4. The holding coil h and the reverse current relay 22, therefore, operate toward the same end, to wit, that the substation shall be retained in operation so long as the power transferred exceeds some predetermined minimum value which makes it desirable to operate the same. Although the relay 22 is constructed as a reverse current relay, it does not function in the manner of the ordinary reverse current relay, and its only action upon a reversal of current will be to short circuit the resistance 22' so that the full voltage of the distribution circuit will be impressed upon the contact-making voltmeter 2. When the conditions of the load on the distribution circuit are such that the power transferred no longer exceeds this certain minimum value, then the master relay 4 will, after the expiration of an interval determined by the setting of the dashpot attached thereto, move to its lower position, and thereby energize, through the contacts of the controller, the switch 25. Power will, therefore, be again supplied to the motor M and brake coil B, and the controller will be moved from the position w to the neutral position x , where the circuit leading to the switch 25 will be broken and the motor and the controller be stopped. The substation is then in condition to be again started as conditions may require.

For the protection of the apparatus involved, certain relays 23 and 24, have been provided. In case of a failure of voltage on the supply circuit A. C., the contacts of the relay 23 will open, and thereupon deenergize the relay 5 and, in turn, the other electromagnetic switches of the substation. If, on the other hand, the power transferred through the substation exceeds a predetermined amount, the relays 24 will be energized and will likewise open the circuit of the relay 5. It may, however, be desirable that the substation should continue in operation and deliver a certain small amount of current, without being entirely discon-

4
nected from the distribution and supply circuits. To this end the relays 19, 20 and 21 have been so arranged that as the power transferred, and hence the current in the alternating current leads, exceeds a certain value, they will open successively and de-energize the magnets 16, 17 and 18 in turn, thereby inserting one or more sections of the resistance 50 between the rotary transformer and the distribution circuit. These resistances will be so dimensioned that their insertion will substantially reduce the power transferred, and at the same time allow the substation to continue in operation and supply some power.

From oscillograph tests, it has been determined that short circuits on a trolley line of limited capacity do not reach their maximum value instantly, but build up to their maximum in approximately five-tenths of a second. Before the expiration of this five-tenths of a second, or in say, two or three-tenths of a second, one or more of the relays 19, 20 and 21 will have come into operation and inserted portions of the resistance 50 between the rotary transformer and the distribution circuit. These relays are provided with dashpots, so that they may open quickly, but will not close until after the expiration of a certain interval of time. In actual practice, it will be found desirable to so adjust the setting of the relay 19 that it will open when approximately 10% overload is reached, while the relays 20 and 21 will open at 25% and 50% overload, respectively. Since the setting of the relay 19 is comparatively low, as contrasted with the necessary high setting of an equivalent circuit breaker, these relays and the short-circuiting switches 16, 17 and 18 controlled thereby are beginning to open before the short circuit has reached its maximum value.

It will thus be seen that I have provided a substation which is entirely automatic, and is operated in accordance with the load conditions of the distribution circuit. I have furthermore, provided a novel and efficient method of protection against overload. I aim to cover in the appended claims not only the particular form of the apparatus which I have herein described, but also any modifications thereof which do not depart from the spirit and scope of my invention.

55 What I claim as new and desire to secure by Letters Patent of the United States, is:—

1. In combination, a supply circuit, a distribution circuit, a rotary transformer, means for connecting said transformer to said circuits, means for mechanically controlling the sequence of operation of said connecting means, and automatic means controlling the operation of said mechanical controlling means.

60 2. In combination, a supply circuit, a dis-

tribution circuit, a rotary transformer, means for connecting said transformer to said circuits, means for mechanically controlling the sequence of operation of said connecting means, and means responsive to the electrical condition of the distribution circuit controlling the operation of said mechanical controlling means.

70 3. In combination, a supply circuit, a distribution circuit, a rotary transformer, means for connecting the same to said circuits, means responsive to the voltage of the distribution circuit controlling said connecting means, and means responsive to the power transferred between said circuits controlling said voltage responsive means.

75 4. In combination, a supply circuit, a distribution circuit, a rotary transformer, means for connecting the same between said circuits, means responsive to a low voltage on the distribution circuit controlling said connecting means, and means responsive to the power transferred between said circuits arranged to produce the effect of low voltage on said voltage responsive means when the power transferred exceeds a predetermined amount.

80 5. In combination, a supply circuit, a distribution circuit, a rotary transformer, means for connecting the same between said circuits, means responsive to the voltage of one of said circuits controlling said connecting means, and means for delaying the action of said voltage responsive means for a predetermined time.

85 6. The combination with a supply circuit and a distribution circuit, of a rotary transformer adapted to be connected therebetween, automatic means responsive to a decrease in the distribution circuit voltage for connecting the transformer to said circuits, means responsive to the distribution circuit voltage for controlling the operation of said automatic means, and means for delaying the operation of said last named means.

90 7. In combination, a supply circuit, a distribution circuit, a rotary transformer, electromagnetic means for connecting the same to one of said circuits, a relay controlling the supply of energy to said electromagnetic means, a controller arranged to energize said relay, and a resistance adapted to be connected in series with said control relay, said controller being constructed and arranged to short circuit said resistance during a short part of its range of movement.

95 8. In combination, a supply circuit, a distribution circuit, a rotary transformer, electromagnetic means for connecting the transformer to each of said circuits, relays controlling the supply of energy to said means, a resistance, and a controller adapted to energize said relays independently of said resistance during a portion of its range of

100

105

110

115

120

- movement and to energize said relays through said resistance during another portion of its range of movement.
9. In combination, a supply circuit, a distribution circuit, a rotary transformer, a plurality of electromagnetic switches for controlling the starting of said transformer, and for connecting the same to said circuits, a motor-operated controller for mechanically determining the sequence of operation of said electromagnetic switches, said controller being arranged to open the circuit of its driving motor when the transformer has been connected to said circuits.
10. In combination, a supply circuit, a distribution circuit, a rotary transformer, a plurality of electromagnetic switches for starting said transformer and for connecting the same to said circuits, means responsive to the electrical condition of the distribution circuit for moving said controller to the position for connecting said transformer to said circuits, and means responsive to the power transferred between said circuits for moving said controller to its initial position.
11. In combination, a supply circuit, a distribution circuit, a rotary transformer, electromagnetic means for starting said transformer and connecting the same to said circuits, an automatically operated controller for energizing said electromagnetic means, a plurality of resistance members connected in series, between said transformer and said distribution circuit, and electromagnetic means arranged to short-circuit said resistance members, said controller being arranged to energize said short-circuiting means in sequence.
12. In combination, a supply circuit, a distribution circuit, a rotary transformer, electromagnetic means for starting said transformer and connecting the same to said circuits, an automatically operated controller for energizing said electromagnetic means, a plurality of resistance members connected in series between said transformer and said distribution circuit, electromagnetic means arranged to short-circuit said resistance members, said controller being arranged to energize said short-circuiting means in sequence, and means responsive to the power transferred between said circuits controlling said short-circuiting means.
13. In combination, a supply circuit, a distribution circuit, a rotary transformer, electromagnetic means arranged to start said transformer and connect the same to said circuits, a controller for mechanically determining the sequence of operation of said electromagnetic means, relays energized from said controller controlling the supply of energy to said electromagnetic means, said controller being constructed and arranged to prevent the further energization of said electromagnetic means through said relays after a momentary interruption of power during the movement of said controller.
14. In combination, a supply circuit, a distribution circuit, a rotary transformer, means for supplying a reduced voltage from one of said circuits to said transformer, means for supplying the full voltage of said circuit to said transformer, and automatic means for mechanically controlling the sequence of operation of said means.
15. In combination, a supply circuit, a distribution circuit, a rotary transformer, means for supplying a reduced voltage from one of said circuits to said transformer, means for supplying the full voltage of said circuit to said transformer, said means being arranged to prevent their simultaneous closure, and automatic means for mechanically controlling the sequence of operation of said means.
16. In combination, a supply circuit, a distribution circuit, a rotary transformer having a field winding, means for energizing said winding from said distribution circuit, means for starting said transformer and for connecting to each of said circuits, and automatic means for mechanically controlling the sequence of operation of said means.
17. The combination with a supply circuit and a distribution circuit, of a rotary transformer adapted to be electrically connected therebetween, said transformer having a sectional field winding, a field resistance, an armature resistance, and automatic means operable, upon a decrease in the distribution circuit voltage, to start said transformer from the supply circuit through a low voltage connection, then to connect the sections of said field winding in series with each other and said field resistance across the distribution circuit, then to short circuit said field resistance, then to operate said transformer from the supply circuit through a high voltage connection, and then to connect said transformer to the distribution circuit through said armature resistance and subsequently gradually render said armature resistance ineffective.
18. The combination with a supply circuit and a distribution circuit, of a rotary transformer provided with a shunt field winding comprising a plurality of sections and adapted to be electrically connected between said circuits, a shunt field resistance, an armature resistance, and automatic means operable in response to an electrical condition of the distribution circuit to start said rotary transformer from the supply circuit through a low voltage connection, then to connect the sections of said field winding in series with each other and with said shunt field resistance across the distribution circuit, then to short circuit said field resistance, then to connect said rotary trans-

former to the supply circuit through a high voltage connection, and then to connect said rotary transformer to the distribution circuit through said armature resistance and 5 subsequently short circuit the armature resistance.

19. The combination with a supply circuit and a distribution circuit, of a rotary transformer provided with a field winding comprising a plurality of sections and adapted to be electrically connected between said circuits, a shunt field resistance, an armature resistance, and automatic means operable in response to an electrical condition 10 of the distribution circuit to start said rotary transformer from the supply circuit through a low voltage connection, then to connect the sections of said field winding in series with each other and with said 15 shunt field resistance across the distribution circuit, then to short circuit said field resistance, then to connect said rotary transformer to the supply circuit to supply power thereto through a high voltage connection, 20 and then to connect said rotary transformer to the distribution circuit through said armature resistance and subsequently short 25 circuit the armature resistance, said automatic means being operable upon a failure 30 of the supply voltage or the distribution circuit voltage to disconnect said rotary transformer from the supply circuit and the distribution circuit.

20. The combination with a supply circuit 35 and a distribution circuit, of a rotary transformer adapted to be electrically connected therebetween, automatic means operable in response to an electrical condition of the distribution circuit to effect the connection 40 of said rotary transformer to the supply circuit and to the distribution circuit, and means coöoperating with said automatic means to effect the disconnection of said rotary transformer from the supply circuit

and from the distribution circuit upon a 45 failure of voltage in either of said circuits.

21. The combination with a supply circuit and a distribution circuit, of a rotary transformer adapted to be electrically connected therebetween, automatic means operable in 50 response to an electrical condition of the distribution circuit to effect the connection of said rotary transformer to the supply circuit and to the distribution circuit, means coöperating with said automatic means to 55 effect the disconnection of said rotary transformer from the supply circuit and from the distribution circuit upon a failure of voltage in either of said circuits, a variable resistance adapted to be connected in circuit between said rotary transformer and the distribution circuit, and means responsive to the power supplied to the rotary transformer to control the insertion and removal of said resistance and, upon said power reaching a predetermined value, to coöperate with said automatic means to disconnect the rotary transformer from the supply circuit and from the distribution circuit. 60

22. The combination with an alternating current circuit and a direct current circuit, one of said circuits being a supply circuit and the other a distribution circuit, of a 65 rotary transformer provided with a shunt field winding and a series field winding and adapted to be electrically connected therebetween, and automatic means operable upon a decrease in the voltage of the distribution circuit to start said rotary transformer from the supply circuit, then to connect said shunt field winding across the distribution circuit and subsequently to connect said rotary transformer to the distribution circuit to supply power thereto. 70

In witness whereof, I have hereunto set my hand this second day of July, 1915.

EDWARD TAYLOR.
